RADIO APPARATUS

John Quincy Gaubert, Dayton, Ohio, assignor, by
mesne assignments, to Radio Corporation of
America, New York, N. Y., a corporation of
Delaware

Application March 9, 1931. Serial No. 521,101

3 Claims. (Cl. 74—7)

This invention relates to radio apparatus and particularly to the driving connections between a control shaft and a tuning shaft, or other driven shafts.

One of the objects of the invention is to provide a smooth, noiseless and efficient driving connection between a control shaft and a driven shaft.

Another object of the invention is to provide a simple and efficient speed reducing drive between a control shaft and a mechanism to be operated thereby.

A further object of the invention is to provide a driving connection between a control shaft and a driven part, in which manipulation of the control shaft beyond the limit of rotation of the movable part will not injure the parts of the mechanism so connected.

Further objects and advantages of the present invention will be apparent from the following description, reference being had to the accompanying drawings wherein a preferred embodiment of one form of the present invention is clearly shown.

In the drawings:

Fig. 1 is a view in elevation with a fragmentary detail illustrating the instant invention.

Fig. 2 is a sectional view substantially as indicated by the line and arrows 2—2 of Fig. 1.

Fig. 3 is a view of the mechanism substantially as indicated by the line and arrows 3—3 of Fig. 1.

Fig. 4 is a front elevational view substantially as indicated by the arrow 4 of Fig. 1.

Fig. 5 is a transverse sectional view through a portion of the device substantially as indicated by the line and arrows 5—5 of Fig. 4.

Fig. 6 is a sectional view of the instant invention illustrating certain portions thereof in modification, the section being illustrated substantially by the line and arrows 6—6 of Fig. 4.

With particular reference to the drawings, the drive mechanism has been illustrated as applied to a tuning unit of a radio apparatus, diagrammatically illustrated as a bank of condensers, but it is obvious that the drive may full well be applied to any form of tuning device, or to any form of rotatable mechanism whether or not it be strictly a tuning mechanism. With this in mind the description will proceed, in that a mechanism 20 having a rotatable shaft 21 is provided with a driving disc 22, the mechanism 20 being secured to a base 23 by screws, bolts, etc. 23a, and to which base is also fixed a bracket 24 having a pair of parallelly extending legs 25 and 26. The leg 26 of the bracket may if desired,

provide a bearing or support for the end of the shaft 21 near the disc 22 as at 27, and it is preferred that the bracket be secured to the base 23 as by screws 28. A convenient form of the bracket as it is to be used in production, conforms to what is known as a U-shaped or J-shaped bracket, in which the bridge portion 24 is secured to the base and the opposite legs 25 and 26 appear as illustrated in Fig. 1.

Each of the legs 25 and 26 of the bracket provides a bearing means for a control shaft 40, the leg 25 providing a spherical depression or recess formed by the tubular squirt or extension 29 while the leg 26 is provided with a notch 30 running from the bridge portion 24 for a substantial distance up the leg 26. The notch 30 is carried over the bend of the bracket joining the leg 26 with the bridge 24 and ends in the arc like aperture 31 in the bridge portion 24, the reason for which will appear presently. A slide member 32 is grooved appropriately to pass through the aperture 31 and along the slot 30, so that the flanges 33 on each side of the groove will act as keepers to retain the slide within the slot 30. The aperture 31 includes lateral notches 34 at the juncture of the slot 30 that permit the flanges 33 to pass through the base 24. This block 32 is provided with a bore 35 within which is journaled the shaft 40 and the shaft 40 carries a collar 36 of complementary surface to properly mate with the semi-spherical squirt 29 hereinbefore described.

These provisions of the squirt 29 and of the collar 36 make for a ball and socket connection between the control shaft 40 and the bearing provided by the leg 25 of the bracket, thus allowing a certain amount of oscillation of the control shaft without the least injury to the parts thereof, or in any way binding of the rotating parts. To secure the collar 36 upon the shaft 40, it has been found only necessary to provide a shallow annular groove 37 near the end of the shaft 40, and thence compress the thin edge of the collar 36 into the groove 37 to act as a retainer therefor substantially as indicated in Fig. 5. On the control shaft 40 there is a driving pinion 45 that may be secured by a set screw 46, and that in all events provides an annular groove of undercut form, as is illustrated at 47 in Figs. 1, 3, 5 and 6. This undercut groove 47 provides an inclined wall or camming surface 48, that is presented for engagement with the driving disc with which it is to be coupled, substantially as indicated in Figs. 1, 3 and 6.

It is thus seen that the control shaft and its 110

assembly of collar 36, slideable bearing 32 and driving pinion 45, may be assembled in a jig placing the members 36 and 45 in proper spaced relation, with the slide 32 interposed somewhere between and sliding upon the shaft 40, at which time the pinion 45 may be secured to the shaft 40, all of which makes for rapid assembly of the structure. When assembling the control shaft with its appertinent members in the bracket 24, it is only necessary to slide the block 32 against the collar 36 then pass the end of the shaft 40 with the parts 32 and 36 thus juxtaposed through the aperture 31 and notches 34 of the bracket 24 so that the slide 32 will match up with the slides of the notch 30 acting as a retainer therefor, thence sliding the assembly laterally through the base and along the notch until the shaft 40 comes into substantial alignment with the squirt 29, when the shaft 40 may be pushed endwise so as to seat the collar 36 in the semispherical depression 29. After so much has been accomplished, the supporting member has a spring 50 that is placed against the block 32 and disposed within the notch 30 beneath the block 32 substantially as illustrated in Figs. 1, 2, 3 and 4, and the bracket is thence secured to the base 23 by the screws 28. This will position the pinion 45 in substantial registry with the edge of the disc 22 so that the groove 47 will receive the peripheral edge of the disc 22 as illustrated in Fig. 1. The spring 50 has been calibrated so that it will continually urge the pinion 45 upwardly or to a point beyond strict alignment with the bearing squirt 29, thus urging the pinion 45 into engagement with the disc 22. The inclined or camming surface 48 engaging the corner of the disc, by means of the spring 50 tends to cant the edge of the disc against the opposite sharpened edge 51 of the groove 47, so that there is frictional engagement between the disc 22 and the pinion 45 at the contacting portions. The engagement thus provided makes for a positive frictional engagement of even tension between the pinion 45 and the disc 22, so that turning of the control shaft 40 produces a smooth and unobstructed rotation of the shaft 21 at all points between its limits of rotation. Upon continued rotation of the control shaft after the driven shaft has been rotated against its stop, no harm is done to the driving mechanism, since slipping will then ensue between the disc and pinion, thus saving the driving mechanism from rupture. In a driving connection of this type, no attention need be given to the strict alignment of parts, such as the shafts 21 and 40, as has heretofore been necessary. The driving engagement between the portions 48 and 51 of the pinion 45 and the disc 22 is infallibly maintained through the engaging portions of the members 45, 51 and 22 and will respond to any degree of misalignment or wear.

It is by no means essential that the spring of the helical form illustrated at 50 be used in the instant invention but one of the bowed or leaf spring type as 60 disclosed in Fig. 6 may be used and in some instances be preferred. In that instance each end of the spring 60 is particularly fashioned so as to make substantial seating engagement with respect to the base 24 and the block 32. This is accomplished by rolling over

the extreme end of a spring at 61, so as to provide a lug that seats in the lateral notches 34 of the aperture 31 in the bridge portion 24 of the bracket. No additional provisions are necessary with regard to the bracket for this adaptation, since the lateral notches 34 are a necessary part of the aperture 31 that provides for the passage of the flanges 33 through the bracket base when the block 32 is assembled therewith. The other end of the spring 60 is flared outwardly at 63 so as to seat within a notch or recess 64 on the under side of the block 32, and thus acts as a confining means for the spring and tends to locate it in correct position. In the first described form the notch 64 on the underside of the block 32 is used for seating the upper end of the spring 50 in a similar manner.

While the form of embodiment of the present invention as herein disclosed, constitutes a preferred form, it is to be understood that other forms might be adopted, all coming within the scope of the claims which follow.

What is claimed is as follows:

1. In a radio apparatus including a slow motion drive for a rotatable shaft, a disc carried by 100 the rotatable shaft, a bracket supporting a control shaft, said bracket providing a socket for a ball and socket bearing for one end of said shaft and a slideable bearing for a second portion of said shaft, a driving pinion secured to 105 the control shaft having an undercut annular groove for the reception of the edge of said driving disc, and means disposed against the slideable bearing urging the pinion into engagement with the said disc whereby the rotation of said 110 control shaft will smoothly drive the disc.

2. In a radio apparatus, means for driving a tuning shaft comprising in combination, a bracket supporting one end of said tuning shaft and providing a pair of substantially aligned bearings, one of said bearings comprising a spherical depression, and the other of said bearings comprising a block slideable within a notch of the said bracket, a control shaft journaled in said slide and providing a ball like collar for disposition within said spherical depression, a drive pinion carried by the control shaft and providing a groove with a camming surface, a disc secured to the tuning shaft having its peripheral edge disposed in the groove of said pinion for 125 driving relation therewith, and a spring support for said slideable bearing urging the camming surface of said pinion into engagement with said disc.

3. In a driving mechanism for radio apparatus having a tuning shaft, the combination including, a bracket supporting one end of the tuning shaft and providing a pair of substantially aligned bearings, one of said bearings comprising a spherical depression, and the other of 135 said bearings comprising a block slideable within a notch of the bracket, a control shaft mounted in the bearing of said block and providing a ball like collar for disposition within said spherical depression, means carried by the control shaft for transmitting motion to the tuning shaft, and means carried by the tuning shaft for engaging said means.

JOHN Q. GAUBERT.
